INSOLE.

No. 895,950.

Specification of Letters Patent. Patented Aug. 11, 1908.

Application filed July 26, 1907. Serial No. 385,703

To all whom it may concern:

Be it known that I, JOSEPH VON BRACHT, a citizen of the United States, residing at Savannah, in the county of Chatham and State of Georgia, have invented new and useful Improvements in Insoles, of which the following is a specification.

This invention relates to inner soles adapted to be used in boots and shoes, and it has 10 for its objects to simplify and improve the construction and operation of this class of devices.

The invention consists primarily in an inner sole which may be in the nature of a complete or a partial sole; that is to say, the principle of the invention may be applied to half soles and to heel cushions as well as to complete soles; said inner sole being in the nature of a detachable or separate member 20 which may be placed loosely within a boot or shoe, or which may be secured, if desired, against displacement in any suitable manner.

Among the objects of the invention are to afford an elastic cushioning device which 25 will form a relief for tender feet.

Another object is to provide a non-conducting device whereby extremes of temperature will be prevented from affecting the feet of the wearer.

Still another object is to provide a ventilating device permitting air to circulate between the soles of the feet and the soles of the shoes, thus furnishing an effective means for checking the objectionable perspiration 35 of the feet to which many are subject.

A further object of the invention is to provide a means which may readily and conveniently be chemically treated or medicated in the application of treatment to the feet.

Still further objects of the invention will be hereinafter fully described and particularly pointed out in the claims.

In the accompanying drawing has been illustrated a simple and preferred form of the invention; it being, however, understood that no limitation is necessarily made to the precise structural details therein exhibited, but that changes, alterations and modifications within the scope of the invention may 50 be resorted to when desired.

In the drawing, Figure 1 is a plan view of an inner sole constructed in accordance with the invention, several of the layers of the material of which it is composed having been 55 partly removed for the purpose of clearly

illustrating the construction. Fig. 2 is a transverse sectional view, enlarged, taken on the plane indicated by the line 2--2 in Fig. 1. Fig. 3 is a transverse sectional detail view illustrating a modification.

Corresponding parts in the several figures are denoted by like characters of reference.

The base of the improved inner sole consists of a strip 1 of leather, textile or other suitable flexible material. This base, which is shaped to fit within the shoe in connection with which it is to be used, and which, as above stated, may form a part of a complete or of a partial sole, serves to support a cellular frame section 2 which may be regarded as 70 constituting a skeleton of the device, and which may be pressed, molded, or otherwise shaped or formed of any suitable material possessing sufficient rigidity and resiliency for the purposes of the invention, such as 75 leather or paper which may be suitably treated with glue, rubber or any other suitable material or composition of matter whereby the necessary qualities of stiffness and resiliency shall be imparted thereto; it 80 being understood however that any suitable material may be employed in the construction of said skeleton. The latter, in the preferred form illustrated in the drawing, is provided with corrugations forming ribs and intervening spaces, which ribs and spaces may be V-shaped as shown in Fig. 2, U-shaped as shown in Fig. 3, or of any other desired shape or outline. This cellular frame is to be 85 glued, cemented or otherwise secured upon 90 the base 1, and the spaces between the ribs adjacent to the upper side of the base constitute air spaces 3, while the cells or spaces 4 intermediate the ribs and adjacent to the upper side of the skeleton 2 serve for the reception of a filling 5 which may consist of 95 cork, wood or fibrous material, or of any other suitable material or substance which is preferably non-conductive of heat. The apices of the ribs 6, are provided with ventilating apertures 7 communicating with the air cells or spaces 3.

Superposed upon the skeleton structure 2, and secured upon the latter in any suitable manner, is a layer 8 of linen, cork, rubber, 105 leather, felt, or any other suitable material which, as well as the filling 5, may be chemically treated or medicated; and above said layer is mounted an external covering strip 9 of linen, leather or other suitable material. 110

Apertures 10—11, registering with the apertures 7, are formed in the strips 8 and 9 respectively. The external covering strip 9 may however be dispensed with, if desired, within the scope of the invention.

From the foregoing description taken in connection with the drawings hereto annexed, the operation and advantages of this invention will be readily understood. The 10 improved inner sole is constructed in such a manner that it will possess in high degree the requisites of resiliency and adaptability to the feet of the wearer as well as non-conductivity of heat and cold, in addition to which 15 free circulation of air adjacent to the feet of the wearer is permitted. The device may be constructed at a moderate expense, and it is thoroughly efficient for the purposes for which it is provided.

20 Having thus fully described the invention, what is claimed as new is:—

1. An inner sole for boots and shoes comprising a top layer provided with openings, a bottom layer, a corrugated frame between

said layers providing upper cells between the 25 openings in the top layer and lower cells provided at their apices with openings between the upper cells and communicating with the openings in the top layer, and a filling of non-conducting material in the upper cells. 30

2. An inner sole for boots and shoes comprising a bottom layer, a top layer formed with perforations, a cellular frame between said layers, said frame being corrugated to provide sets of alternately arranged upper 35 and lower cells between the same and the respective layers, the lower cells being open and provided with apertures in the apices thereof registering with the apertures in the top layer, and a filling of non-conducting 40 material in the upper cells.

In testimony whereof, I affix my signature in presence of two witnesses.

JOSEPH VON BRACHT.
